ELECTRON MULTIPLIER DEVICE

Russell R. Law, Princeton Township, Mercer County, N. J., assignor to Radio Corporation of America, a corporation of Delaware

Application August 12, 1948, Serial No. 43,851

24 Claims. (Cl. 179—171)

1

In this application, I disclose an improved electron multiplier device wherein a large amount of electron multiplication is produced as a result of secondary emission initiated by a relatively small number of electrons.

The electron discharge device of my system is of wide and general use in the electron art. My invention is especially useful for translating, amplifying, generating and/or controlling radio frequency power.

An object of my invention is to provide an improved electron discharge device of the beam type for generating considerable power of very high frequency.

A further object of my invention is to provide improved means for increasing greatly the magnitude of high frequency currents or voltages.

An additional object of my invention is to provide an electron multiplier system of the secondary emission type which provides more electron multiplication than any electron multiplier system known in the art.

A further object of my invention is to provide in a beam tube an electron multiplier of the secondary emission type which is suitable for use where high power at high frequency is to be generated.

Another object of my invention is to provide an improved electron multiplier of the secondary emission type for generating and controlling or modulating the magnitude of large amounts of high frequency currents or voltages.

A specific object of my invention is to provide an improved dynode element which makes possible high frequency, high power electron multiplication.

Attainments of the objects mentioned above and others which will appear hereinafter is made possible by my novel device for multiplying electrons. This device comprises, in a beam type electron discharge device, electrodes including an electron emission source, novel electron collector or target electrode structure, and a plurality of novel electron multiplier elements in groups effectively in parallel between the electron emission source and the electron collector electrode structure. In specific embodiments, some of the electron multiplier elements of my invention are triangular in form with inwardly curving sides to guide the electrons to the secondary electron emitting dynodes which are roughly rectangular with inwardly curving sides. Although the dynodes are small in cross section, the spacing is close and a large number of elements are used to give large output currents. Other

2

novel features are included, such as differentially arranged collector electrodes and a novel electron beam blocking electrode which cooperates with the beam deflection or sweep to provide a differential output which may be modified as to magnitude and phase by shaping the beam blocking electrode edges to correct for non-linearity in the device or to provide a non-linearity.

In describing my invention in detail, reference will be made to attached drawings wherein Figure 1 illustrates diagrammatically and by symbols an electron multiplier system arranged in accordance with my invention and comprising parallel groups of multiplier elements. This figure also illustrates the collector electrode or electrodes and the manner in which corresponding dynodes or electron multiplier elements are strapped together to operate certain ones thereof at like potentials, and, groups thereof at unlike potentials.

Figure 2 illustrates schematically a beam source, beam deflecting electrodes, an electron multiplier assembly arranged in accordance with my invention and a target or electron collector electrode structure in the beam path.

Figure 3 illustrates schematically a modification of the arrangement of Figure 2. In Figure 3 there is a flat beam source. Figures 2 and 3 illustrate also the manner in which operating potentials may be supplied to the electrodes of my novel electron discharge devices including the deflecting elements. Figure 3 illustrates my novel knife-edge beam blocking electrode interposed between the deflecting elements and my novel electron multiplier electrode assembly.

Figures 4, 5, 6, 7, 8 and 9 illustrate in detail the shape of the dynode electrodes, the manner in which they are supported and grouped and how they are positioned relative to the collector electrodes. In Figure 4, the dynodes and one collector electrode are shown in perspective with portions in cross section to better illustrate the structure thereof.

Figures 10 and 11 illustrate the manner of mounting the dynodes and collectors within a sealed envelope. Figure 10 is a plan view partly in cross section through an axis of the tube on which both collectors are seen. Figure 11 is a perspective partly in section through the axis of the electron discharge device at right angles to the section on which Figure 10 is taken.

Figures 12, 13, 14 and 15 illustrate details of the electron gun which emits the electrons in a wide concentrated sheet toward the dynode elements. These figures also illustrate the beam

focussing and deflecting electrodes and the manner of mounting the gun in the electron discharge tube. Figure 12 is a cross section on the line 12—12 of Figure 14. Figure 14 is a cross section on the line 14—14 of Figure 13, and Figure 15 illustrates the knife-edge beam blocking electrode as mounted in the electron gun structure. Figure 15 is a cross section view on the lines 15—15 of Figure 12. Figure 16 shows the beam blocking electrode in perspective.

In Figure 1 it is assumed that an elongated beam of electrons is produced and fed in the direction indicated by the arrows to the input of an electron multiplier system arranged in accordance with my invention. The elements marked *a*, *a'*, etc. are focussing or steering electrodes and serve the purpose of guiding the electrons toward the multiplier electrodes or dynodes *b*, *b'*, *c*, *c'*, *d*, *d'*, *e*, *e'*, *f*, *f'*, *g*, *g'*, *h*, *h'*. Of these elements, *b*, *b'*, etc. are herein designated as input electrodes, since the electrons from the source are guided to the surface thereof to release secondary electrons which pass to the next row of elements to repeat the electron multiplying process. Electron trajectories are shown. The elements *b*, *b'*, etc. constitute the first electron multiplier stages and also serve the purpose of steering the electrons toward the next row of elements *c*, *c'*, etc. In Figure 1, I have shown electron multiplier elements *b* to *h* inclusive. It will be obvious that the number of electron multipliers in each row may be increased to increase the multiplying effect. Moreover, a plurality of rows as shown, or more rows, or fewer rows, may be provided. By virtue of the amplification by secondary emission at each successive multiplier stage, only a relatively small number of electrons from the source need be controlled to correspondingly control a very large number of electrons reaching the electron collector electrodes. This reduction in necessary driving power makes it possible to use beam deflection control in amplification and modulation of high frequency currents. In contrast with grid control, class-C operation is possible at very high frequencies. The amount of driving power needed to control, by beam deflection, the small number of electrons used in the input of my novel electron multiplier is reduced and it thereby becomes practical to control the power generation by, for example, control potentials or modulation potentials of very high frequency because uniform velocity electrons may be injected into the multiplier in very short pulses. Inasmuch as the total transmit time through the multiplier is of no import, the only frequency limitation arises from transit time dispersion which tends to smear the pulses. As will appear hereinafter, electron dispersion is reduced to a negligible amount in my improved dynode assembly. In Figure 1 it is assumed that the collector electrodes No. 1 and No. 2 are insulated each from the other and the output is taken from both electrodes as described hereinafter. It will be understood that my electron multiplier system may be used with a single collector output.

Figure 1 also illustrates the manner of applying operating potentials to the dynode electrodes. As shown hereinafter, the electron multiplier groups are effectively in parallel in the beam path between the electron source and the collector electrodes. Moreover, the parallel groups of dynodes may feed a single collector electrode or a pair of separate collector electrodes. In

applying operating potentials, the electron multiplier elements may also be grouped in parallel in another manner. For example, steering electrodes *a*, *a'*, etc. may be strapped together as shown diagrammatically at *Sa* to operate at like direct current potentials. These straps are shown in the group at the right of Figure 1 but the straps for applying direct current potentials have not been shown as being connected to the group of elements at the left of Figure 1, since this would interfere with the clearness with which other features are illustrated. Dynodes *b*, *b'*, etc. are connected in parallel by a strap *Sb*, while dynodes *c*, *c'*, etc., of each of the other rows are similarly grouped in parallel with respect to applied direct current potentials. The potentials applied to the straps *Sa* to *Sb* may be increasingly positive relative to the direct current potential on the electron source electrode but these electrodes in practice are less positive than the collector electrodes. The electron input is from the top of the diaphragm and the electrons are to be visualized as being introduced through the elements *a*, *a'*, etc., of the first row, which serve as the steering electrodes so that the electrons strike on dynode electrodes *b*, *b'*, etc., which constitute the first electron multiplier stages. From the dynode electrodes *b*, *b'*, etc., some of the primary electrons introduced from the source and those electrons which are released from the dynode surfaces are drawn to electrodes *c*, *c'*, etc. Again the primary electrons and secondary electrons are drawn toward the following dynodes *e*, *e'*, etc., so that finally a very large number of electrons reach the collector electrodes through each series of dynodes and the total electron stream to the collector electrodes No. 1 and No. 2 is a great many times greater than the original electron stream, in fact, may be in amperes.

Returning to the straps *Sa*, *Sb*, etc., we may assume that strap *Sa* is at potential 1, strap *Sb* at potential 2, etc., so that in the embodiment described there are eight different direct current potentials applied to the groups of elements. If the number of dynodes grouped in this manner is increased, the magnitude of the final current is increased with a corresponding increase in the number of direct current potentials and strapping elements for the added groups of dynodes. The essential features to be kept in mind in connection with Figure 1 is the fact that many elements are put in parallel. The figure is not drawn to scale, but each dynode, *c*, *d*, *e*, etc. has a top dimension of the order of 75 thousandths of an inch and a height slightly more than the width. With the spaces between dynodes of corresponding scale, ten stages of the electron multiplier of my invention then occupies a space less than one inch long. Ten stages in parallel—ten deep—might then occupy a one inch square area and have a length appropriate for the electron beam provided.

Since control of a very small number of electrons controls an exceedingly large number of output electrons, my invention has made possible the use of beam deflection control of the initiating electrons to thereby control the final output. Such deflection control systems have been shown schematically in Figures 2 and 3 of the drawings. In Figure 2, the two collector electrodes No. 1 and No. 2 might each be fed by a multiplier section (shown in part only) which might be of the order of two inches high, two inches wide, and one inch deep. The sections may be treated as a single multiplier assembly

and the dimensions thereof may vary through a wide range. A somewhat concentrated beam of electrons is supplied from cathode A and fed between the deflector elements or plates B and C. The beam when at rest is focussed to fall at a point on the multiplier assembly intermediate the four boundaries thereof, preferably about half way between the upper and lower boundaries and half way between the extreme side boundaries thereof. When control potentials are applied to the deflecting plates B—C, the beam is swept across the entrance to the multiplier in a horizontal direction so that first collector No. 1 and then collector No. 2, and vice versa, are predominantly supplied with output current. Deflection serves to spread the electrons of the beam across the multiplier structure in a horizontal direction. Space charge spreads the electrons in a vertical direction as they go through the multiplier. The deflecting plates B—C may be excited by a signal voltage of the desired frequency which may be very high. Any appropriate coupling means may be used. In an example given, a transformer coupling CT is used. The $r-f$ output appears in a circuit OT coupled differentially to the collector electrodes.

In the embodiment of Figure 3, A represents an electron source which emits a wide flat beam of electrons drawn by the collector electrode through the deflection plates B—C. This beam is focused by the deflecting electrode plates B—C to line L on the blocking electrode D—E. The letter L represents the position of rest of the beam. Portion D blocks emission toward collector No. 2 when the beam is swept up above L and portion E blocks emission toward collector No. 1 when the beam is swept down below L. Now assume an alternating current voltage AC is applied to the deflection plates B—C to deflect the beam in a vertical arc first upward and then downward. Since the beam at rest is on the line L, electrons will not pass by the blocking electrode until the deflecting voltage has approximately reached its crest F as shown schematically by the curve in Figure 3 adjacent to electrode D—E. Similarly when the deflecting voltage reverses and the beam is deflected in the opposite direction, the beam will not pass the electrode D—E until the voltage has reached the value F'. Had the deflection been relatively greater than the beam would have been passed the knife edge electrode sooner in the electrical cycle, for example, at the electrical positions G and G'. If the edges O and P of the blocking electrode are made other than a straight line and parallel, a desired modulation characteristic may be obtained. Such an electrode might be employed to correct for non-linearity in the device or to specifically provide a desired non-linearity. When electrodes as shown diagrammatically in Figure 3 are used, the collector electrodes may be as illustrated in Figure 1 and the output is in effect differential.

The electron multiplier and collector electrode assembly is shown in perspective in Figure 4 with portions broken away to show the structure of the steering and dynode elements, and their relation to each other and to the collector electrodes. Roughly $\frac{1}{2}$ of the assembly, in the third quadrant, and one collector electrode is shown. The electrodes have been labelled as in Figure 1 and it will be noted that the depth of the assembly of Figure 4 is not as great as that of Figure 1. More specifically, in Figure 1 layers a to h inclusive are shown whereas in Figure 4 layers

a to f are shown. The dynodes are all initially of like cross section area having the form of dynodes c to f or h, inclusive. Elements a and b are then formed by cutting away a portion of the metal as at X in Figure 4. Fragments only of dynodes c, d, e and f are shown in order to show better the manner of assembling the dynode electrodes and mounting the same in front of the collector electrodes. The individual elements cut away as at X, Figure 4, or in their original form are formed at the ends as illustrated in Figures 6, 7, 8 and 9 with extensions 10 that are spot welded to apertured metal discs 14. The elements are off-set or staggered on the various discs so that interleaving of the elements take place as shown in Figures 1 and 4. For example, the metal disc nearest the cathode may carry elements "u," "u," etc. and the next metal disc then would carry elements "b," "b," etc. The elements "a" and "b" are off-set or staggered. The third and fourth discs then carry elements "c" and "d" respectively and these dynode elements are staggered as fastened to the discs to facilitate compact assembly and proper reflection of the electrons. Disc 14 of Figures 7 and 8 is assumed to carry dynodes as at c, Figure 1. Since the groups a, b, c, etc. operate at different direct current potentials, the discs 14 are, with exceptions explained hereinafter, assembled as shown in Figures 4 and 5 between mica or the like insulating discs 16. In order to get the proper spacing, apertured metal discs 18 as shown in Figures 8 and 9 are spot welded to each side of the disc 14. The elements 14 and 18 may be of one or two or three or more pieces as desired. The mica discs 16 are similar in shape to the discs 14 and cooperate with the larger aperture in the filler members or discs 18 to provide long leakage paths between the groups of dynodes on the discs 14. An enlarged cross section of the dynode assembly is shown in Figure 5.

Each collector or target electrode has a bombarded block 20 with slots or channels 21 therein spaced so that the edges of the dynode elements of alternate rows remote from the electron gun are within the slots thus assuring that nearly all of the electrons leaving the final dynode elements fall on the collector electrodes. The portions 23 of the collector electrodes are integral with or fastened to anode bases 22, 22' which have cooling fluid openings therein to withdraw heat from the high power anodes. This cooling fluid circuit is not being claimed herein and is not shown and described in detail. The general character thereof is shown in Figures 10 and 11 which also show the manner of mounting the dynode and collector assembly of the prior figures. Figures 10 and 11 taken with the remaining figures also show the essential features of the electron gun, deflecting electrodes and their mounting in an electron discharge device arranged in accordance with my invention. In the sake of simplicity, like parts are designated by corresponding reference numerals, letters and symbols throughout the several figures insofar as possible.

Figure 10 is a cross section through the longitudinal axis of the tube while Figure 11 is a cross section through the longitudinal axis of the tube at right angles to the section in Figure 10. 40 is a main element support base which comprises a heavy copper ring member to which is fastened, by a vacuum tight joint, a lower base shell 42. The base shell 42 has soldered or otherwise fastened thereto a kovar metal truncated cone-like

member 44 to which the lower glass cap 46 is fastened by a vacuum tight seal. The glass cap member 46 supports the tubular kovar elements 48 and 48' which are sealed into glass base 46 and have several functions. These members support the base blocks 22 and 22' for the collector electrodes No. 1 and No. 2. They also serve as output connections for the collector electrodes and for the direct current paths to the collector electrodes and are tubular for circulating a cooling medium through the collector electrodes. The cooling circuit, per se, is not being claimed herein and details of the fluid circuit have been omitted. The collector electrodes No. 1 and No. 2 are shaped in the embodiment being described substantially as disclosed here and in the prior figures.

An upper main element support 50 takes the form of a heavy copper ring with counter sunk bolt holes therein. Bolts 52 are passed therethrough and threaded into registered openings in the main support base 40. The dynode structure described in detail above and illustrated in Figure 5 is clamped tightly between the elements 40 and 50. The output dynode adjacent the collectors may run at ground potential and in the embodiment being described it is so assumed. Then the discs 14, 18 on which the final dynodes are mounted are clamped tightly in contact with the main base ring 40 as shown in Figure 5. This is also illustrated in Figures 2 and 3 as described hereinafter where the final dynode is grounded. Three discs 14 only are shown in Figure 5 but more may be added. The first disc 14 is insulated from the tube base and other tube elements by an insulating disc 16.

An upper base shell 54 is fastened to the ring 40 and extends up over the outer periphery of the ring 50 and is flanged inwardly to cover the lower outward extending flange of a cup-like closure member 56. These joints are vacuum tight and the cup-like member 56 is sealed to a smaller cup-like member 58 through which the various electrode leads other than the anode leads extend. These leads 62 are sealed through a glass top member 60 which is sealed to the top end of cup-like member 58. Corresponding leads 62' are sealed in a second glass member 64 fastened to a flanged ring member 66 which is slid into the member 58. Metallic connector members 68 slip over the ends of leads 62 and 62' to complete these circuits and make it easy to assemble the electron discharge device elements.

As shown in Figure 11, the flanged member 66 which slides into the end cap 58 is supported by two U-shaped channel stands 70 and 70' cut away at 71 for clearance. These stands are flanged at the lower ends and bolted to the top main element 50 by bolts 74 to hold the elements 62', 64, 66 rigidly in alignment with the tube structure.

The electron gun assembly including the cathode, the deflecting electrodes and knife-like blocking electrode are supported by a rectangular-like member 100, Figures 5, 10, 11, 12, 13, 14 and 15 with one dimension much greater than the other to accommodate the flat, wide electron beam and elongated cathode, knife-like electrode, etc. (Figure 3). The member 100 is flanged outwardly at its lower end 101 and spot welded to the apertured metal disc 14 used to support the steering electrodes a, a' and this disc 14 is clamped tightly between main support members 40 and 50. The steering electrodes, deflecting electrodes B-C and aperture electrode may all

operate at the same potential which is different than the potential at which the output dynodes operate. To obtain this operation the end 101 and disc 14 to which it is fastened is insulated from base ring 50 by a mica disc 16.

The open ended box-like member 100 is cut away at the upper portion at each end as shown at 102, Figures 13, 14 and 15, to accommodate the electron gun structure. The upper end of the cut away box member is flanged outwardly at 103 along its longest dimension to provide a support for the cathode and deflecting electrodes and knife edge blocking electrode. Two double offset aperture electrode members 104 and 104', supporting electrode structure described in detail hereinafter, extend into the rectangular can 100 and are fastened to the flanges 103 by bolts or spot welding at the points 106. These electrode support members 104 and 104' are assembled and the electrodes fastened thereto before they are placed in the box 100. The electron beam, emitted by cathode 108, Figure 14, passes down through off-set members 104, 104' and toward the dynode elements. The cathode 108 is heated by filament wires 109. The cathode 108 is of considerable axial length as shown in Figures 12, 13 and 14 and is supported on metal rods 112, spot welded at points 114 to a U-shaped metal rod 116 mounted in ceramic beads 118. Rotation of the U-shaped rod is prevented by its shape. The ceramic beads 118 are held in place by metal straps 122, spot welded to the top of the double off-set members 104 and 104'. The leads to the heating elements 109 are omitted in the sake of simplicity but may extend from adjacent ends of filaments 109 toward the connectors 62'. Then the remaining adjacent ends of filaments 109 are connected together. The deflecting electrodes may comprise metal or a metallic deposit on insulating material such as mica with connections thereto. In the drawings they are represented at 124 and 124'. The double off-set members 104 and 104' have cut away portions leaving legs 126 and 126' to which the members 124 and 124' are fastened at 128 (Figure 12). In the sake of mechanical strength, the edges of the cut away portions are turned outwardly at 127 and 127', Figures 12 and 14. The sides of leg members 126 and 126' are treated in like manner at 129 and 129' to stiffen the structure. To further strengthen the structure, strap-like braces 131 and 131' are spot welded or otherwise fastened to portions 127 and 127' of the two off-set members 104 and 104' to hold them rigidly in the desired spaced relation. Strap members 133 and 133' serve a similar purpose for the legs 126 and 126' and also serve as a support for the knife edge electrode described hereinafter.

The off-set members 104 and 104' are fastened or strapped together at points 131 and 131' and 133 and 133' and the electrodes mounted therein before the structure is assembled in the rectangular can 100. Then the entire apparatus is dropped into the can 100 and spot welded as described above at points 106.

The knife-like blocking electrode D-E as shown in Figures 12, 13, 14, 15 and 16 has extensions 138 and 138' thereon which extend through the space between the legs 126 and 126' of members 104 and 104' and are turned down as at 139 and 139' to be spot welded to the straps 75 at 133 and 133' to hold the knife edge blocking

electrode E—D in a plane which extends partially across the path of the beam.

The relation of the electron multiplier electrode of my invention to the beam forming electrodes will now be described. This multiplier electrode comprises a plurality of dynodes effectively in layers when considered as traversing the path of the beam and in parallel when considered with respect to the electrons passing through the electrode assembly from the cathode to the collector electrodes. The separate elements of each group, for example, elements *a*, *a'* and/or elements *b*, *b'* and/or elements *c*, *c'*, etc. are mounted in metallic disc-like rings 14 having rectangular apertures therein and the elements are built up in layers and laid in positions transverse to the beam path. The dynode stacks are then positioned between the members 40 and 50 to be clamped in place. The cathode beam focussing and knife edge electrodes are also mounted in a member 100 fastened to an apertured disc-like member 14 which is clamped between members 40 and 50. Relative adjustment of the dynode and electron gun assembly is easily made and the structure after alignment is clamped tightly in place by means of bolts 74.

My electron discharge device may be put to various uses in the electronic art. No attempt will be made to list all of such uses here. It may be used as an R. F. amplifier and in Figures 2 and 3 I have shown circuit connections for putting my novel tube to such use. In these basic diagrams I have included only the essential features. Variations will be obvious to those skilled in the art. In these figures the tube electrodes are numbered as in the prior figures. The cathode 103 may be indirectly heated by an A.-C. source. R. F. is applied by coupling transformer CT to the deflecting plates 124—124'. D. C. potentials are applied as shown. The values of D. C. potentials given are merely by way of example and may be changed as desired to meet different tube electrode spacing, different uses, etc. In Figure 2, deflection sweeps the beam in a direction to cause it to pass back and forth from No. 1 to No. 2 collector and vice versa. The output then appears in the differential A.-C. circuit OT. In other words in Figure 2 the beam sweep is in a direction at right angles to the sweep of the beam in the embodiment of the following figures. This involves merely an appropriate change of the deflection elements 124—124' to set up the deflection force as desired. In both embodiments amplified R. F. is taken from the output coupling transformer OT. As stated above, the dynode stages operate at different potential and are insulated from each other. The final stage may operate at ground potential as shown in Figures 2 and 3 and its disc 14 is in contact with ring 40 also conductively connected to ring 50, etc. The initial dynode stage may operate at the potential at which the knife edge electrode D—E, Figure 3, and aperture electrodes 104, Figures 2 and 3, operate and to permit such operation closure member 100 and the disc 14 to which it is fastened are insulated from main base ring 50 by an insulating disc 16 as shown in Figure 5.

From the foregoing description it is obvious that I have provided new and improved electron discharge device means for multiplying electrons to an extent greater than possible heretofore and various novel electron discharge device features and circuits which take part in providing in-

creased electron multiplication and means for controlling the character of the electrons as multiplied. It is also clear that variations may be made in the apparatus and means of the embodiment shown without departing from the spirit of my inventions or set forth in the claims which follow.

I claim:

1. An electron multiplier comprising at least three spaced dynode elements, each element having two concave secondary electron emitting surfaces on opposite sides thereof, the dynode elements being staggered so that secondary electrons released from two dynode elements fall on the secondary electron emitting surfaces of an intermediate dynode element.
2. An electron multiplier assembly comprising at least three spaced dynode elements, each element having two concave secondary electron emitting surfaces on opposite sides thereof, the dynode elements being staggered so that secondary electrons released from one element fall on secondary electron emitting surfaces of the remaining two dynode elements.
3. An electron multiplier structure comprising at least three rows of dynode elements, the dynode elements of the middle row each having two concave secondary electron emitting surfaces and being displaced with respect to the elements of the remaining rows so that electron flow takes place from the elements of the middle row to the elements of the other two rows.
4. An electron multiplier as in claim 1, wherein said dynode elements are interposed between a primary electron source and a collector electrode.
5. An electron multiplier as in claim 4, further including an electron focussing electrode positioned between said source and said dynode elements to guide primary electrons toward the secondary electron emitting surfaces of said two dynode elements.
6. An electron multiplier structure comprising at least three rows of dynode elements, the dynode elements of the middle row having two concave secondary electron emitting surfaces and being displaced with respect to the elements of the remaining rows so that electron flow takes place from the elements of the middle row to the elements of the other rows, means for feeding electrons to the dynode elements at one of said rows and a collector electrode for receiving multiplied electrons from the dynode elements at the other ends of said rows.
7. An electron multiplier structure including a plurality of rows of dynode elements each having two concave active electron releasing surfaces, the dynode elements in adjacent rows being displaced in position so that flow of electrons may take place between the curved active surfaces in adjacent rows, and an electron focussing electrode having two concave surfaces at the input end of at least one of said rows.
8. An electron multiplier structure including at least three rows of dynode elements, the elements of end rows having at least one active concave electron releasing surface facing the inner rows, the elements of the inner rows having two active concave electron releasing surfaces facing in opposite directions, and means for feeding electrons to be multiplied to the dynodes at adjacent ends of said rows.
9. An electron multiplier device including a plurality of rows of dynode elements each having two concave electron releasing surfaces, the dynode elements in adjacent rows being displaced in

position along the length of the rows so that flow of electrons between rows takes place, means for feeding electrons to be multiplied to dynode elements at one end of said rows, and an electron collector electrode for receiving multiplied electrons from the dynode elements of the other ends of said rows.

10. An electrode structure comprising an apertured substantially non-emissive metallic disc and a plurality of elongated dynode elements each mounted across said aperture and each having at least one active concave electron releasing surface.

11. An electrode structure comprising an apertured metallic disc and a plurality of dynode elements mounted in spaced relation across said aperture, certain of said elements having two substantially opposed concave surfaces for receiving electrons passing through said aperture.

12. An electron beam tube, comprising an electron multiplier electrode assembly including at least three rows of dynode elements, each row having a plurality of dynode elements including initial and final elements, an electron collector electrode comprising an active surface wherein channels are formed and means for mounting said electron multiplier electrode and electron collector electrode in fixed relation with portions of the final dynode elements of alternate rows positioned in said channels.

13. An electron discharge device comprising, in combination, an electron source, two electron collector electrodes in the path of emission from said source, a knife edge blocking electrode in a plane transverse to the said electron path, said knife edge blocking electrode comprising apertures in opposed quadrants of a circle having its origin substantially in the axis of the path of the electron beam when at rest and deflecting electrodes adjacent the path of said beam between the electron source and said knife edge blocking electrode.

14. An electron discharge device, comprising a source of electrons, an electron target electrode comprising a channeled active surface, and at least three rows of electron multiplier electrodes interposed between said source and said target electrode.

15. An electron discharge device, comprising a source of electrons for producing an electron stream along a predetermined path, an electron target electrode toward which the electrons are directed, three or more rows of electron multiplier electrodes interposed between said source and said target and electron stream deflecting electrodes on opposite sides of said path and between said source and said electron multiplier electrodes.

16. A beam tube comprising in combination, an apertured main support member, a closure member at one side thereof fastened thereto and including an insulating member, a target electrode supported by the insulating member and extending into said aperture, an electron multiplier electrode clamped to the other side of said support member and comprising in series dynode elements with the final elements facing said target electrode in said aperture, an electron beam source mounted on the other side of said support member to feed electrons to the initial dynode elements, and a closure member fastened to the said other side of said main support member and enclosing said beam source.

17. A beam tube comprising, a metallic support member having an aperture formed therein, a closure member on one side thereof fastened

5 thereto, a target electrode supported by said closure member and insulated therefrom and extending into said aperture, said target electrode comprising an active surface wherein channels are formed, an electron beam source mounted on the other side of said support member for producing an electron beam and directing it toward said target electrode, an electron multiplier electrode positioned between said electron beam source and said target electrode, said electron multiplier electrode comprising a plurality of parallel rows of dynode elements with the final dynode elements of alternate rows interposed in said channels, deflecting electrodes positioned between said beam source and the initial dynode elements of said parallel rows, and a closure member fastened to the other side of said main support member for enclosing said beam source, deflecting electrodes and multiplier electrodes.

10 18. A beam tube comprising, a metallic support member having an aperture formed therein, a closure member on one side thereof fastened thereto, a target electrode supported by said closure member and insulated therefrom and extending into said aperture, said target electrode comprising two active surfaces in each of which channels are formed, an electron beam source mounted on the other side of said support member for producing an electron beam and directing it toward said target electrode, an electron multiplier electrode structure positioned between said electron beam source and said target electrode, said electron multiplier electrode structure comprising a plurality of parallel rows of dynode elements with the final dynode elements of alternate rows interposed in said channels, deflecting electrodes positioned between said beam source and the initial dynode elements of said parallel rows, a knife edge blocking electrode between said source and said multiplier electrode structure, and a closure member fastened to the other side of said main support member for enclosing said beam source, deflecting electrodes, knife electrode and multiplier electrodes.

25 19. A beam tube comprising in combination, a metallic support member having an aperture formed therein, a closure member on one side thereof fastened thereto, a target electrode supported by said closure member and insulated therefrom and extending into said aperture, said target electrode comprising two active surfaces insulated each from the other, an electron beam source mounted on the other side of said support for producing a flat, wide electron beam and directing it toward the active areas of said target electrode, an electron multiplier electrode structure positioned between said electron beam source and said target electrode, deflecting electrodes between said beam source and said electron multiplier structure to sweep said beam over said active surfaces simultaneously, a knife edge blocking electrode between said deflecting electrodes and said electron multiplier structure, said knife edge blocking electrode comprising a member positioned across the path of the beam and having apertures in opposite quadrants of a circle, the center of which is on the beam axis when at rest, and a closure member fastened to the other side of said main support for enclosing said beam source, deflecting electrodes, knife edge electrode and electron multiplier electrode.

30 20. A beam tube comprising in combination, a support member having an aperture formed

therein, a closure member on one side thereof fastened thereto, an electron beam source mounted on the other side of said support member for producing an electron beam and directing it toward said aperture, a target electrode supported by said first named closure member and insulated therefrom and extending into said aperture in the path of said beam, said target electrode comprising two active surfaces insulated from each other, an electron multiplier structure positioned between said electron beam source and said target electrode, said electron multiplier electrode structure comprising dynode elements with initial elements in the path of said beam and final elements adjacent said active surfaces, deflecting electrodes positioned between said beam source and the initial dynode elements and arranged to deflect said beam back and forth between paths directed toward the respective surfaces and a closure member fastened to the other side of said main support member for enclosing said beam source, deflecting electrodes and multiplier electrodes.

21. An electron multiplier tube including a target electrode, an electron beam source for directing a beam of electrons toward said target electrode along a predetermined path, electron beam deflecting means on opposite sides of said path, an electron multiplier structure comprising three or more rows of dynodes elements in parallel between said source and said target electrode, an envelope for said electrodes and connections through the wall of said envelope for applying operating potentials to said electrodes.

22. In combination, an electron discharge device including a target electrode, an output circuit coupled thereto, means for directing a beam of electrons toward said target electrode, an electron multiplier electrode including at least three rows of dynode elements interposed between said means and said target electrode, deflecting electrodes interposed between said means and said electron multiplier electrode, an input

circuit coupled to said deflecting electrodes and connections to groups of said dynode electrodes for applying thereto potentials which increase progressively by steps as the dynode element distance from said means increases.

5 23. In combination, an electron discharge device including two target electrodes insulated from each other, a differential output circuit connected to said target electrodes, a beam source for directing an electron beam toward said target electrodes, at least three rows of electron multiplier electrodes in parallel between said beam source and each of said target electrodes, beam deflecting electrodes adjacent the path between the beam source and target electrodes and an input circuit coupled differentially to said beam deflecting electrodes.

10 24. An electron multiplier assembly comprising a plurality of electrode structures as claimed in claim 11 stacked in spaced relation with apertured insulating members between said discs.
